UNITED STATES PATENT OFFICE.

WILLIAM A. LEE, JR., OF NEW YORK, N. Y.

GILL-BOX.

No. 813,654.

Specification of Letters Patent.

Patented Feb. 27, 1906.

Application filed May 3, 1905. Serial No. 258,737.

To all whom it may concern:

Be it known that I, WILLIAM A. LEE, Jr., a citizen of the United States, and a resident of the borough of Brooklyn, county of Kings, city and State of New York, have invented certain new and useful Improvements in Gill-Boxes, of which the following is a specification.

My invention relates to gill-boxes, a class of machines employed for drawing out and leveling wool either before or after it is combed. Such machines commonly comprise two or more sets of rolls, between which the wool passes successively and is drawn and reduced in thickness by driving one set of rollers at a greater surface speed than the other, while the leveling of the wool is obtained by means of bars (termed "fallers") provided with pins engaging the wool while it is being drawn and traveling in the same direction as the wool. According to the manner of disposing of the product three types of gill-boxes are distinguished: can-gills, having cans to receive the web or "sliver," as it is called, (sometimes the sliver is allowed to drop on an apron, dispensing with the can;) spindle-gills, in which the web after being twisted (in which case it is called a "slubbing") is wound on a bobbin, and balling-gills, in which the material after passing between the rolls is wound or balled by means of balling-rolls.

My invention is applicable to each of the three types above mentioned, and has for its object to insure an improved operation in the following respects: First, to obtain a constant "draft," by which term I mean the ratio of the speed with which the sliver is drawn or delivered to the speed with which the sliver enters the machine. The detailed description following hereinafter will explain the difficulties which the customary gill-boxes present in this particular. Second, I improve the action of the stop-motion or knock-off motion, which is intended to stop the machine after a certain length of material has been delivered, but which does not fulfil this purpose satisfactorily in ordinary gill-boxes. Third, in all gill-boxes aprons are employed for drawing the sliver, which aprons draw more or less, according as they are new or worked into shape, even though their speed be the same. I have provided means for adjusting the draft of these aprons without altering the ratio of delivery speed to entrance speed. Fourth, with special ref-

erence to spindle gill-boxes and balling gill-boxes, I have added to them a set of press-rolls or take-up rolls, with advantages fully stated hereinafter.

Reference is to be had to the accompanying drawings, in which—

Figure 1 is a plan view of so much of a can gill-box as is sufficient to illustrate my invention, with parts omitted for the sake of greater clearness. Fig. 2 is a vertical section taken substantially on line 2 2 of Fig. 1. Fig. 3 is a cross-section on line 3 3 of Fig. 2; and Figs. 4 and 5 are vertical sections similar to Fig. 2, illustrating the application of my invention to a spindle gill-box and a balling gill-box, respectively.

A can gill-box comprises three sets of principal rollers—the back rolls A, which feed the material into the machine; the front rolls B, which, together with the apron C, passing between them, draw out the sliver as the front rolls rotate at a higher rate of surface speed than the back rolls, and the press-rolls or take-up rolls D, which control the delivery of the sliver. I have not illustrated the fallers E in detail, as they may be of the customary construction; but it will be understood that they extend parallel with the roll-axes and travel forward from the back rolls to the front rolls, their upwardly-projecting pins E' engaging the forwardly-traveling sliver and their ends E'' meshing into the threads of the screws F F'. G indicates the drive-shaft, commonly called the "back" shaft, which by means of bevel-gears G' and spur-gears G² drives the screws F F', controlling the movement of the fallers, in the usual way, the fallers dropping when they reach a point near the front rolls, then traveling backward in their lower position and rising again when near the back rolls. All these parts may be of the customary construction, and I have therefore deemed it unnecessary to illustrate them fully.

My invention consists particularly in the manner of driving the front rolls, the press-rolls, and the knock-off motion. The back rolls A may be driven in the usual way by gearing H, which generally includes change-gears, so that the relation of the back-roll speed to that of the fallers may be varied. The front rolls B are driven by gearing J, which includes change-gears or other means for varying the speed of the front rolls without altering the speed of other parts of the machine. The press-rolls D are driven by

gearing K, either directly from the back rolls A or, as shown, from a wheel of the train of gearing H or from the back shaft G, or in any other way that will preserve a constant ratio of speed between the back rolls and press-rolls—that is, a constant rate of draft. I prefer to drive the press-rolls from the back-roll gearing H. Of course change-gears will generally be included in the gearing K, so that the rate of draft may be varied, if desired; but as long as the gearing K is unchanged the rate of draft will remain constant and will not be affected by any adjustment of the front-roll speed. The knock-off motion is driven directly from the press-rolls D, as by gearing L, which may include change-gears. With this arrangement (as long as the gearing L is unchanged) the machine will stop automatically after a constant number of revolutions of the press-rolls, or, in other words, after delivering a predetermined length of the product.

The apron C, being made of leather or other material and working in conjunction with the fluted front rolls B, is at first practically smooth when new, but gradually becomes corrugated transversely owing to the pressure of the intermeshing roll-flutings. An apron when new will therefore draw less material per revolution of the front rolls than after the apron has become shaped to the flutes of the rolls. Since, however, the press-rolls take up and deliver the material at a constant rate of speed, it follows that with a new apron there is danger of the material being drawn too hard between the front rolls and press-rolls and not enough between the front rolls and fallers. To overcome this difficulty, the gearing J is adjusted to properly increase the speed of the front rolls B when a new apron is inserted. It will be observed that such adjustment has not the least effect on the draft—that is, on the rate of speed of press-rolls to back rolls. Should the speed of the front rolls be increased too much, the portion of the material between the front rolls and press-rolls will become slack, thus showing the operator that the speed of the front rolls should be reduced. This slackness will also appear as soon as the apron C becomes corrugated in use, and consequently draws more material per revolution of the front rolls than it did when new. The operator will then substitute the necessary change-gear to reduce the number of revolutions of the front rolls. It will therefore be understood that my invention provides means for adjusting the speed of the front rolls as may be required by the varying condition of the apron C without affecting the rate of draft—that is, if the press-rolls D take up and deliver the material six times as fast as it is fed by the back rolls A this relative rate of speed or draft will be preserved irrespective of any adjustment of the front-roll speed. This is

not the case, however, when the press-rolls are driven from the front rolls, as has been the practice hitherto.

As regards the advantage of driving the knock-off motion direct from the press-rolls, it will be obvious that this insures the delivery of a predetermined length of sliver, since the press-rolls (being generally smooth) always feed the same length of material per revolution. Heretofore it has been the custom to drive the knock-off motion from the front rolls, which, as above stated, feed more or less per revolution, according to the varying condition of the apron. The knock-off motion, which is operated after a predetermined number of revolutions, will therefore in this old arrangement be irregular in its action as regards the length of material delivered.

When applying my invention to gill-boxes of the spindle type or balling type, as shown in Figs. 4 and 5, respectively, I may arrange the back rolls, front rolls, and fallers in exactly the same manner as hereinbefore described. In the spindle gill-box, Fig. 4, even the press-rolls are exactly the same as in Fig. 2, and the only difference between the two structures is that the sliver is twisted into a slubbing after passing between the press-rolls and is wound on a bobbin M in the same manner as in ordinary spindle gill-boxes. I may here remark that spindle gill-boxes as usually constructed have no press-rolls, but simply a stationary guide-rod.

In the balling gill-box, Fig. 5, inasmuch as the sliver is wound on the customary bobbin N, resting on the balling-rolls O and movable upwardly as the balling operation progresses, the press-rolls D are arranged at different levels, and I prefer to employ three rolls—two at the same level and the third at a different level and in an intermediate position—that is, forward of one roll and in the rear of the other. Balling gill-boxes as heretofore constructed have no press-rolls between the front rolls and the balling-rolls.

The advantage of adding press-rolls, as described, in gill-boxes of the spindle type and balling type lies in the feature of making the knock-off motion dependent directly upon the speed of the press-rolls, which therefore become measuring-rolls to stop the machine after the required length of material has been delivered. The addition of press-rolls when driven as described also preserves a constant rate of draft, as has been fully explained in connection with the can gill-box. It will be understood that in all three types of machines when equipped according to my invention the knock-off motion is driven at a constant rate of speed relatively to the back rolls and is not to be affected by any change in the speed of the front rolls.

Various modifications may be made without departing from the nature of my invention.

I claim—

1. In a gill-box, the combination, with the back rolls, the front rolls, and the press-rolls arranged to take up the material after its 5 passage between the front rolls, of connections for driving the press-rolls and the back rolls, a separate connection for driving the front rolls, so that a variation in the speed of the front rolls will not affect the speed of the 10 press-rolls, and a knock-off motion governed by the number of revolutions of the press-rolls.

2. In a gill-box, the combination, with the back rolls, the front rolls, the apron passing 15 between the front rolls, and smooth press-rolls arranged to take up the material after its passage between the front rolls, of connections for driving the press-rolls and the back rolls, and a separate connection for driving the front rolls, so that the variation in the 20 speed of the front rolls will not affect the speed of the press-rolls.

3. In a gill-box, the combination, with the back-rolls, the front rolls, the apron passing 25 between the front rolls, and the press-rolls arranged to take up the material after its

passage between the front rolls, of connections for driving the press-rolls and the back rolls, a separate connection for driving the front rolls, so that the variation in the speed 30 of the front rolls will not affect the speed of the press-rolls, and a knock-off motion governed by the number of revolutions of the press-rolls.

4. In a gill-box, the combination, with the back rolls, the front rolls, the apron passing between the front rolls, and the smooth press-rolls arranged to take up the material after its 35 passage between the front rolls, of connections for driving the press-rolls and the 40 back rolls, and a separate connection for driving the front rolls, so that a variation in the speed of the front rolls will not affect the speed of the press-rolls.

In testimony whereof I have hereunto set 45 my hand in the presence of two subscribing witnesses.
